3 Sheets Drawing. 9 Pages Specification

A combine harvester thresher with an auxiliary cylinder and concave for rethreshing the tailings and a stone trap to protect the rethresher from damage by rocks and other hard objects in the tailings. The stone trap is a box with an open top in communication with an opening in the rethresher. Hard objects such as rocks are driven into the stone trap by the rotating cylinder in the rethresher. A door on the stone trap can be opened to remove the hard objects.
